Primary Examiner — Philip S Hyder

(74) Attorney, Agent, or Firm — Boyle Fredrickson, SC

(57) **CLAIM**

The ornamental design of a handle grip pad, as shown and described.

DESCRIPTION

FIG. 1 is an isometric view of a handle grip pad incorporating my new design, wherein the portions illustrated in dotted lines form no part of the claimed design;

FIG. 2 is a left side elevation view thereof, the right side elevation view being a mirror image thereof;

FIG. 3 is a front elevation view thereof;

FIG. 4 is a rear elevation view thereof;

FIG. 5 is a top plan view thereof; and,

FIG. 6 is a bottom plan view thereof.

1 Claim, 6 Drawing Sheets
